(57) **CLAIM**

The ornamental design for a memory storage device with surfboard housing, as shown and described.

DESCRIPTION

FIG. 1 is an exploded perspective view of the memory storage device with surfboard housing showing our new design;

FIG. 2 is an exploded top view thereof;

FIG. 3 is an exploded side view thereof, the opposite side being a mirror image;

FIG. 4 is an exploded bottom view thereof;

FIG. 5 is a front view thereof;

FIG. 6 is a rear view thereof; and,

FIG. 7 is a perspective view thereof.

The broken lines showing of the attachment cord in FIGS. 1-7, and the pattern of the connector in FIGS. 1, 2 and 4 are for illustrative environmental structure and form no part of the claimed design.
